UNITED STATES PATENT OFFICE.

JOHN S. MURPHEY, OF BALTIMORE, MARYLAND, ASSIGNOR TO JOHN W. MEALY & SONS CO., OF BALTIMORE, MARYLAND, A CORPORATION OF MARYLAND.

WATCH-HOLDER FOR PERSONAL WEAR.

1,101,498.

Specification of Letters Patent. Patented June 23, 1914.

Application filed August 8, 1912. Serial No. 713,951.

To all whom it may concern:

Be it known that I, JOHN S. MURPHEY, a citizen of the United States, residing at Baltimore, in the State of Maryland, have 5 invented certain new and useful Improvements in Watch-Holders for Personal Wear, of which the following is a specification.

This invention relates to a safety watch holder for personal wear and has for one of 10 its objects to provide a simple and attractive watch holder which will securely retain the watch and prevent accidental displacement and loss while being worn on the person.

Another object of the invention is to provide 15 an improved watch holder which may be readily attached to a strap, band, chain or other retaining device whereby it may be worn on the wrist, and when so worn to secure the watch against detachment.

With these and other objects in view, the 20 invention is illustrated in the accompanying drawing wherein,

Figure 1, shows a front elevation of the improved holder, with a watch in place 25 therein and also shows in perspective a band in the form of a bracelet for attaching the same to the wrist of a person. Fig. 2, shows a rear elevation of the holder, watch and a portion of the attaching band, and Fig. 3, 30 illustrates the holder in front perspective.

In the drawing the holder comprises a plate, 1, slightly concavo-convex in shape and having a central opening, 2, and a plurality of circumferential, or rim-edge, clip-fingers, 3, 35 to engage the circumferential edge, 4, of a watch, 5, when the latter is laid on the holder. The holder also has a stem-engaging arm, 6, which extends radially from the circular plate and has a goose neck curved 40 extremity, 10, which is slotted to embrace the stem or post, 7, of the watch below the usual attaching ring, 8, of the latter. This arm, 6, and its curved extremity is provided with a slot, 9, which extends radially with 45 respect to the center of the holder plate and the inner end of said slot is open and communicating with the central opening, 2. The width of the slot, 9, is such as to allow the watch stem or post, 7, while projecting 50 through the opening, 2, to enter and slide along the slot during the act of attaching or detaching the watch. The central opening, 2, at the inner end of the slot, 9, is provided as the most symmetrical and convenient 55 form of entrance opening for the watch

stem and ring into the slot but obviously this entrance to the slot need not be central with respect to the holder plate.

To attach the watch to the holder the post or stem and the ring, 8, of the watch are 60 passed from the front or concave side through the opening, 2, to the rear side of the holder so as to insert the post in the open end of the slot, 9, after which the post may be slid along to the outer end of the 65 slot where the closed goose-neck curved end, 10, of the arm, 6, will extend around the front side of the watch stem, as shown in Fig. 1. The rim or circumference, 4, of the watch is then pressed against the concave 70 side of the holder plate until the clip fingers, 3, snap into engagement with said watch rim, thus clamping the watch in place. These clip fingers, 3, however are not relied upon alone to secure the watch in place because under sudden jars or jolts the watch 75 may become displaced therefrom. In case however such disengagement of the fingers, 3, should take place the watch could not drop out of the holder as long as the rear 80 or convex side of the latter is held close against the part of the person to which the holder is attached, because the watch stem or post would still be engaged by the goose-neck curved arm, 6, and disengagement from 85 the latter can only take place by providing sufficient space at the rear side of the holder to enable the watch ring and stem to be turned rearwardly, which could not be done 90 while the holder plate, 1, is confined against some part of the person.

The particular means for attaching the holder to the person may vary, but in the case of a lady's arm bracelet, the holder is provided with diametrically opposite lugs, 95 11, each having a slot, 12, so that a band, strap or chain, 13, may have ends connected to said slotted lugs and also have a fastening such as a buckle, 14, or other device to enable the band or encircling device to be 100 passed about the person's wrist and secured in place. When worn as a bracelet it will be understood that the rear side of the holder will be held close against the wrist or arm and that while so held it will be impossible 105 to remove the stem of the watch from the stem-engaging arm, 6, and accidental loss will therefore be prevented even if clip fingers, 3, shall become disengaged or broken off.

Having thus described my invention what I claim and desire to secure by Letters Patent is:-

1. A bracelet watch holder formed from a single piece of metal comprising a plate against which the closed back of a watch case may seat said plate having a plurality of outwardly extending lugs to engage the rim-edge of a watch case and also having two spaced apart metal strips extending outwardly therefrom and connected at their outer ends to form an integral arm,—the space between the arm-strips extending from the connected outer end of said strips inwardly and into the plate proper and being of sufficient area to permit the ring, stem and post of the watch to pass therethrough the connected ends of the arm strips being offset from the plate proper a sufficient distance to extend across the outer side of a watch post when the watch is seated against said plate and means for attaching a bracelet-end to said plate.
2. A bracelet watch holder formed from a single piece of metal comprising a plate

against which the closed back of a watch case may seat said plate having a plurality of outwardly extending lugs to engage the rim-edge of a watch case and also having an integral arm which also projects outwardly and forwardly for a sufficient distance to extend from the under closed side of the watch case to the outer side of the post of the watch which the plate is to hold, said arm having a slot which extends from the forwardly projecting portion thereof back into the plate which slot is of sufficient area to permit the ring, stem and post of the watch to pass, and the metal of the arm across the outer end of the slot serving to embrace the outer side of the watch-post while the lugs of the plate engage the rim of the watch case, and means for attaching a bracelet-end to said plate.

In testimony whereof I affix my signature in presence of two witnesses.

JOHN S. MURPHEY.
